H. N. ROCHE.
ELECTRIC WATER HEATER.
APPLICATION FILED DEC. 21, 1909.

967,058.

Patented Aug. 9, 1910.

UNITED STATES PATENT OFFICE.

HERBERT N. ROCHE, OF SAN FRANCISCO, CALIFORNIA, ASSIGNOR TO THOMAS B. GRAY,
OF SAN FRANCISCO, CALIFORNIA.

ELECTRIC WATER-HEATER.

967,058.

Specification of Letters Patent.

Patented Aug. 9, 1910.

Application filed December 21, 1909. Serial No. 534,346.

To all whom it may concern:

Be it known that I, HERBERT NOSWORTHY ROCHE, a citizen of the United States, residing in the city and county of San Francisco and State of California, have invented new and useful Improvements in Electric Water-Heaters, of which the following is a specification.

This invention relates to water-heaters, 10 and pertains particularly to instantaneous electric heaters.

The object of my invention is to provide an electric water-heater that will fully meet and satisfy the exacting requirements of 15 boards of fire underwriters, and municipal building regulations relating to electrical apparatus; to provide, in combination with an electric water heating unit, mechanism whereby a standard snap switch is actuated 20 in unison with and automatically by a water-controlling valve; and to provide mechanism whereby an electric circuit is instantaneously closed after a desired volume 25 of liquid is permitted to flow through the heater and by which the circuit is broken just before the flow of fluid is stopped, thereby preventing the burning out of the coils.

Other purposes of the invention will be set forth in the specification.

30 The invention consists of the parts and the construction and combination of parts as hereinafter more fully described and claimed, having reference to the accompanying drawings, in which—

35 Figure 1 is a side elevation of the device, partly broken away. Fig. 2 is a central, vertical section partially in elevation. Fig. 3 is a plan view of the switch mechanism. Fig. 4 is a perspective of a standard, two-pole snap switch. Fig. 5 is a perspective of the coupler. Fig. 6 is a sectional view of same. Fig. 7 is a section on line α — α Fig. 2. Fig. 8 is a detail of the racks and pinions. Fig. 9 is a perspective of a portion 45 of the coil insulator.

An important feature of my invention is in the employment of a suitable snap switch, as for instance a form of which is shown at 2, secured to a cap 3, of suitable insulating material, forming a cover for a water-receiver 4.

The switch and receiver are inclosed in a casing 5 having a crown 6 surmounted by an incandescent light bulb 7. The lower end

of the casing is closed by a bottom 8, of suitable insulating material, to which is fastened a base 9 having a conveniently attached valve casing 10 provided with a valve 11 adapted to be opened and closed by a handled stem 12.

If the valve, shown closed, be opened water will pass upwardly through the perforated bottom 9 in the receiver 4, and around and between suitably connected, heating coils 13 nested in a tubular insulator 14, thence downward through a central insulated pipe 15, and escaping through an adjustable, removable spout 16 connected to the base 9.

The terminals 17 of the series of coils 13 are conveniently fastened in appropriate binding-posts 18, in the cap 3 of the water-receiver 4, and the posts 18 are suitably connected, as by lead wires 19, to spring posts 20 of the switch 2. The switch is also provided with other spring posts 21 to which are secured the main feed wires 22 which are brought up through the base 9 and within the casing 5, and when the usual rotary switch-stem 23 is turned, the switch blades 24 will snap successively in one direction into and out of contact with spring posts 20—21, thus, when in contact, completing a circuit from one main across the switch, through the coils 13, thence again across the switch, and out over the other main.

It may here be stated that to the posts 20 are secured conductors 25—26 leading to the lamp 7 which consequently will be lighted whenever the coil circuit is closed.

An essential and important feature of my invention resides in providing mechanism in combination with the switch which will be reliable, effective and safe in operation; and which may be manipulated, with a very small exertion of energy, in conjunction with the valve 11.

It is my aim to permit the valve to be opened to nearly its full extent without danger of short-circuiting the circuit-closing mechanism, or of closing the circuit; and to insure the instantaneous operation of the switch as the flow of water is cut off.

Suitable means may be employed to transmit power from the valve stem 12 to the switch 2, and to this end I secure to the valve stem a pinion 27 engaging a rack 28.

slidable in a bearing 29 secured to the base 9. The rack extends upwardly within the casing 5, and is connected by a rod 30 to a plate 31 bearing short racks 32-33 guided 5 in a frame 34 fastened to the cap 3, Figs. 1 and 3. The racks 32 and 33 are shown as being placed out of line, relatively, and each is adapted to mesh, on opposite sides, with flanged pinions 35-36, which are 10 loosely mounted upon a shaft or coupler 37, journaled in the frame 34, Fig. 6. The coupler shaft 37 is threaded as at 38, and is screwed upon the switch stem 23, and has fastened upon it flanges 39 and 40 abutting 15 the adjacent actuating pinions 35-36 respectively. The pinion 35 carries a spring-pressed pawl 35' adapted to engage shoulders 41 on the flange 39, and likewise the pinion 36 carries a pawl 36' adapted to 20 engage shoulders 42 on the flange 40.

The operation of the switch-throwing mechanism is then as follows: When the valve stem 12 is turned to permit the water to flow, it raises the rack 28, and the racks 25 32 and 33 turn their coacting pinions 35 and 36 in opposite directions, the pawl 35' falling into engagement with shoulder 41 on the flange 39, and thus turning the coupler shaft 37 clockwise. The valve stem 12 may 30 be turned to allow the desired volume of water flow from the spout 16, without being heated, and if it is desired to heat the water the valve stem is turned to the fullest extent, and just before the limit of motion is 35 reached the pawl-driven coupler-shaft 37 turns the switch stem 23 sufficiently to allow the switch-blades 24 to snap around and close the electric circuit through the heating coils 13. The switch remains in this 40 closed position until the valve-stem 12, being turned down to stop the flow of water, rotates the pinion 36 carrying its pawl 36' upwardly into engagement with a shoulder 42 on the flange 40 of the shaft 37, and just 45 prior to the closing of the valve 11, the coupler 37 will throw the switch 2 and break the heating circuit. As stated the racks 32 and 33 are disposed on opposite sides of the pinions, and these are loose on the shaft 37, 50 consequently the pinions will turn in opposite directions at each reciprocation of the rack-rod 30. The pawl 35' turns the shaft 37 each time the rod is raised, and the pawl 36' is effective to turn the shaft in the same 55 direction each time the rod is lowered. Thus the shaft is intermittently revolved in one direction, and therefore may be used in conjunction with a standard or suitable snap switch, such as is commonly required by 60 building laws and boards of underwriters. It will therefore be seen that the valve may be opened to allow the discharge of cold water, and slightly more opened if it is wished to heat the coils electrically, and to 65 heat the water. After the electric circuit

has been closed, it remains so until the valve is nearly closed when the snap switch is actuated and interrupts the circuit.

To protect the apparatus against damage from the possible contingency of the lack of water in the service system, I may provide at a convenient point in the coils 13, within the receiver, a fuse or its equivalent 43 which will melt and sever the continuity of coil circuit in the absence of water at the 75 fuse.

It is understood that where reference is made to insulating material in this specification that any suitable substance best adapted to the requirements may be employed.

The bulb 7 serves as a means for indicating that the circuit is closed, and for general illumination, while the hot water is running from the valve.

85

The structure provided enables a person to so open the valve as to obtain nearly the full capacity of the service without operating the switch, and also enables one to so reduce the volume of water discharged from 90 the nozzle that the entire heating efficiency of the coils may be utilized to heat this small volume to the desired temperature.

Fig. 9 shows extensions of insulating tubes for the purpose of protecting the terminals 95 from water contact. The extension of the tubes at the bottom is for the purpose of insulating the heating unit from the metal bottom of the tubes.

Suitable insulation is placed between the 100 apparatus and the water pipe.

Having thus described my invention, what I claim and desire to secure by Letters Patent is—

1. In a water heater, the combination of 105 a receiver, inlet and discharge connections thereto, an electric heating unit in said receiver, a rotatable snap-switch, and means including a longitudinally movable member associated with the inlet connection, and a 110 member engaged and rotated thereby and connectible to the switch.

2. In an electric water-heater, a receiver, an inlet valve and a discharge connection for the receiver, an electric heating unit in the 115 receiver, a snap switch, a coupler therefor, and means operatively connecting said coupler and the valve, said means comprising a slidably mounted rack connected to the water valve, a pinion engaged and rotated by 120 said rack, and connections between the pinion and a member of the switch.

3. An electric water-heater comprising a water-receiver, an electric heating unit there-in, a valve for controlling the flow of water 125 through the receiver, a snap switch operative to connect said unit and mains, a coupler shaft adapted to operate the switch in one direction, and means connecting said shaft and the valve, said means comprising 130

- a slidably mounted rack connected to the water valve, a pinion engaged and rotated by said rack, and connections between the pinion and a member of the switch. 25
- 5 4. In a water-heater, an electric heating unit, current supply mains, a snap switch adapted to complete an electric circuit through said unit and said mains, and means operative in conjunction with a supply valve 10 of the water-heater whereby the switch is closed when water is admitted to the heater, and is opened when the valve is closed to cut off the water, by intermittent rotation in one direction, said means comprising a slidably mounted rack connected to the water valve, a pinion engaged and rotated by said rack, and connections between the pinion and a member of the switch. 15
5. In a water-heater, a water-receiver, a valve controlling the flow of water into said receiver, an electric heating unit contained in the receiver, electric feed mains, a switch interposed between said mains and said unit, 20
- a coupler for said switch, and mechanism adapted to operate said coupler in one direction, said mechanism including pawl-carrying pinions loose on the coupler, and racks for said pinions connected to the valve. 25
6. The combination in a water-heater of a water-container, an electric heating unit, 30 an electric current controlling switch, a cock controlling the water supply, a pair of pinions loosely turnable upon a shaft, rack bars actuated in unison with the turning of the cock to turn the pinions in opposite directions, connections between the pinion shaft and the snap switch, and pawls adapted to act alternately to rotate the switch in a single direction. 35

In testimony whereof I have hereunto set 40 my hand in the presence of two subscribing witnesses.

HERBERT N. ROCHE.
